United States Patent

Des. 237,849

Patented Dec. 2, 1975

237,849

COOLING RACK

James M. Hale, Chicago, Ill., assignor to Xerox
Corporation, Stamford, Conn.

Filed Apr. 29, 1974, Ser. No. 465,392

Term of patent 14 years

Int. Cl. D6—99

U.S. Cl. D6—142

FIG. 2

FIG. 3

FIG. 5

FIG. 6

FIG. 1 is a perspective view of a cooling rack according to the invention;

FIG. 2 is a front view of the cooling rack;

FIG. 3 is a right side view of the cooling rack;

FIG. 4 is a top plan view of the cooling rack, taken along lines 4—4 in FIG. 3;

FIG. 5 is a rear view of the cooling rack; and

FIG. 6 is a left side view of the cooling rack.

I claim:

The ornamental design for a cooling rack, as shown.
